UNITED STATES PATENT OFFICE.

THOMAS W. MILLER, OF ASHLAND, OHIO, ASSIGNOR TO THE FAULTLESS RUBBER COMPANY, OF ASHLAND, OHIO, A CORPORATION OF OHIO.

BEAD-FORMING MACHINE.

1,359,265.

Specification of Letters Patent. Patented Nov. 16, 1920.

Application filed May 1, 1920. Serial No. 378,165.

To all whom it may concern:

Be it known that I, THOMAS W. MILLER, a citizen of the United States, residing at Ashland, county of Ashland, State of Ohio, have 5 invented certain new and useful Improvements in Bead-Forming Machines, of which the following is a specification.

My invention relates to machines for forming rolls or beads at the edges or open 10 ends of dipped tubular rubber articles, such as toy balloons, finger cots, nipples, and the like, and has for its primary object to provide an improved machine adapted simultaneously to roll the beads on a plurality of 15 such articles.

My invention also embraces certain minor details of construction as hereinafter more definitely will be pointed out and claimed, reference being had to the accompanying 20 drawings, in which:—

Figure 1 is a perspective view of my improved machine.

Fig. 2 is a similar view of a conventional dipping board showing thereon a plurality 25 of toy balloon forms.

Fig. 3 is an enlarged transverse sectional view, taken on the line III—III of Fig. 4.

Fig. 4 is an enlarged detail horizontal 30 sectional view of a portion of the machine.

Fig. 5 is an enlarged detail sectional view 35 of one of the bead forming rollers and its spindle.

Fig. 6 is an enlarged detail sectional view 40 of a balloon form with the dipped balloon shown thereon, said form being positioned between the bead forming rolls, also shown in transverse section.

Fig. 7 is a view similar to Fig. 6, showing the bead formed.

Fig. 8 is a detail vertical sectional view.

Fig. 9 is a plan view of the stop guides on the form receiving table.

Similar numerals of reference denote corresponding parts in the several views.

In the said drawings, the reference numeral 1 denotes the bed plate of the machine, the same being suitably supported on legs 2. Detachably mounted on side brackets 3, by means of bolts 4, and at the rear of the 45 machine, is a housing 5 adapted to receive a series of gears 6, said gears being operated by a belt pulley 7 mounted upon the shaft 8 of one of the gears, said housing being provided with a removable top 9 and being 50 formed liquid-tight to receive a suitable

lubricant for said gearing. With respect to said gearing, it is sufficient that the same be arranged, as shown, to rotate, the shafts 10 in pairs in opposite directions, the direction of rotation of the pulley 7 being in the 60 direction of the arrow in Fig. 4, whereby the pairs of spindles 10 will be rotated upwardly toward each other. Mounted upon the bed plate 1, and substantially coextensive in length therewith, is a vertically movable 65 table 11, the same being guided in said bed plate by rods 12 passing through apertures in the latter and having coiled therearound springs 13, tending normally to maintain said table 11 in its uppermost position. 70 Fixed to the ends of said table are guide plates 14, the width of the same corresponding with the thickness of the table, said plates projecting forwardly and widened at 14' and having their vertical edges slightly 75 beveled outwardly, as shown. The means for vibrating the table 11 vertically comprise a lever 15 fixed to a pivot rod 16 running transversely across the machine and at its other end having fixed thereto a lever 17, 80 said levers 15 and 17 being pivotally connected with the ends of the table 11 by suitable links 18, as shown. The free end of the lever 15 is guided by a strap 19 bolted to the side of the machine, said strap having an 85 upper stop-screw 20 and a lower similar stop-screw 21 therein, whereby the vertical movement of the free end of said lever 15 may be controlled as hereinafter described. Attached to said lever 15 intermediate its 90 length is a rod 22, extending downwardly and connected to a suitable foot-lever (not shown.)

Mounted transversely of the table 11, and extending for some distance forwardly 95 thereof, are metal brackets 23, the same being disposed in mortises in the upper surface of said table and having mounted therein elongated anti-friction rollers 24 disposed to project but slightly above the top surface of the table 11, for a purpose herein-after to be described. As an additional guide for the vertical movement of the table 11, I provide suitable slotted brackets 25 bolted thereto and projecting upwardly at 100 the rear thereof, said brackets being engaged by pins 26 fixed to brackets 27 bolted to the bed plate 1, as shown in detail in Fig. 3. Also mounted on the table 11 at the rear thereof are a plurality of angle irons 28 105 110

slotted to receive retaining screws 29, engaging the underside of the table 11, and projecting at their vertical portions above the upper surface of said table at the rear 5 thereof, as shown in Figs. 8 and 9. The vertical portions of said brackets have passing therethrough adjusting screws 30 engaging apertures in the table 11, suitable springs 31 being mounted on said screws to 10 retain said brackets constantly in their rear-most positions against the heads of said screws 30, in a manner readily understood.

The projecting spindles 10 are slotted at their outer ends, as best seen in Fig. 5, and 15 have detachably mounted thereon coating spindles 32, the same being provided with cross pins 33 to engage in the slots in the ends of said spindles 10 to prevent independent rotation. Molded or otherwise attached to said spindles 32 are elongated rolls 34 formed of any suitable soft material, preferably sponge rubber, said rolls being tapered at their front ends to points, as shown.

25 From the above description the operation of my improved machine will be understood as follows: When it is desired to operate to the capacity of the machine, so far as its length is concerned, all of the spindles 10 are provided with rollers 34, and the usual form-carrying board 35 having fixed thereto the forms 36, which previously have been dipped in the rubber solution to form thereon the articles, such as balloons, as shown, 30 is slid horizontally into position along the anti-friction rollers 24 from the front of the machine, the widened portions 14' of the guide plates 14 positioning the same with sufficient accuracy during this operation until the rear edge of the board contacts with the stop plates 28. In this position the width of the board 35 is such that it has passed completely beyond the widened portions 14' of the guide plates 14 and is 35 free to move transversely of the machine. This action is highly desirable in order that the stems of the forms 36 passing between the pairs of bead-forming rolls 34 may come to position properly, which is facilitated 40 greatly by the action of the anti-friction rolls 24, which permit a free lateral movement to the board 35 supported thereon. With the board 35 in position, which is shown in Figs. 3 and 4, and it being understood 45 that the rolls 34 are being rotated rapidly and in unison from the pulley 7, the bead-forming operation may be effected with great rapidity by depressing the treadle at the lower end of the rod 22, which 50 results in bodily depressing the table 11, this movement being limited by the position of the lower set-screw 21 in the strap 19, through its contact with the free end of the lever 15. This movement of the table 11 causes the rollers 34 to exert their rolling

action upon the lower edge of the rubber deposited upon the forms 36, thereby rolling the same into the desired bead, the two steps of this operation being shown clearly in Figs. 6 and 7, the position of the board 35 70 in Fig. 6 being that shown in Fig. 3, while Fig. 7 illustrates the relative position of the rolls 34 and the forms when the table 11 is depressed as described. The operation of rolling the beads being completed by the depression of the foot treadle, the latter is released and the table 11 resumes its normal uppermost position, its rise being limited by the adjusted position of the upper screw 20 in the strap 19. The board 35 then may 80 be removed and the operation repeated indefinitely by the insertion of the successive form-carrying boards.

I have illustrated in Fig. 2 a conventional dipping board 35, which contains two rows 85 of forms 36, each row containing twelve forms. With a machine adapted to operate on such a board, it will be seen that twenty-four articles are rolled at one operation of said machine. It will be understood, however, that I do not limit myself to any particular number of forms, as it is evident that by elongating the bead-forming rollers 34 and similarly enlarging the table 11 laterally, two boards 35, or a board of double 90 width carrying forty-eight forms may be carried in the machine and operated on simultaneously. In fact I do not wish to limit myself in any respect as to the number of rows of forms 36 which may be operated on, as it is evident that they may be increased to operate upon six or more rows of forms, though in this case it may be necessary to provide means for temporarily positioning and supporting the outer ends 105 of the rollers 34 while in operation. Nor do I wish to limit myself to the number of forms 36 disposed longitudinally of the boards 35 as they may vary in number as desired, the limit, of course, being that imposed by the number of rolls 34 on the machine.

It will be observed that the housing 5 containing the gearing for carrying and operating the rollers 34 is removable from 115 the machine, and for the purpose of operating upon different sized forms, I contemplate the use of different sized housings 5 carrying properly spaced spindles 10 to accommodate forms of any character. In 120 other words, these dipped articles are made in various sizes, and the stems of the forms 36 vary more or less in size, which renders it desirable that a single machine may be capable of adaptation to these different sizes 125 of spindles by the substitution of different housings 5 carrying suitable gearing and spindles 10.

As seen in Fig. 1, the stop-screws 20 and 21 may be adjusted as desired to vary the 130

limit of movement in either direction of the lever 15, which correspondingly will limit the movement of the table 11, whereby the latter may function properly with forms of different lengths, and also may vary the length of the material rolled on the forms to suit different conditions, as may be desired. In a similar manner the angle irons 28 may be adjusted toward or from the rear edge 5 of the table 11, to vary the adjusted position thereon of the form carrying boards 35.

Having thus described my invention, what I claim as new and desire to secure by Letters Patent, is:—

15 1. In a bead forming machine, means for forming the beads simultaneously upon a plurality of rows of articles to be treated.

2. In a bead forming machine, bead forming means, means for positioning a plurality 20 of rows of articles to be treated in operative relation to said bead forming means, and means for shifting the relative positions of said parts simultaneously to form the beads.

25 3. In a bead forming machine, a series of rotatable bead forming rolls arranged in pairs, means for positioning a plurality of rows of articles to be treated on forms between said pairs of rolls, and means for

30 shifting the relative positions of the parts simultaneously to form the beads.

25 4. In a bead forming machine, a series of rotatable bead forming rolls arranged in pairs, means for positioning a plurality of rows of articles to be treated on forms between said pairs of rolls, and means for shifting the position of the articles to be treated simultaneously to form the beads thereon.

40 5. In a bead forming machine, a pair of rotatable bead forming rolls, means for positioning therebetween in fixed relation a form carrying an article to be treated, and means for shifting the relative positions of said parts whereby said rolls will form the bead on said article.

45 6. In a bead forming machine, a pair of rotatable bead forming rolls, means for positioning therebetween in fixed relation a form carrying an article to be treated, and means for moving said form longitudinally to cause said rolls to form the bead thereon.

50 7. In a bead forming machine, a pair of horizontally disposed rotatable bead forming rolls, a vertically movable table normally disposed to receive thereon a form carrying the article to be treated in position between said rolls, and means for depressing said table and form to cause said rolls to 55 form the bead on said article.

60 8. In a bead forming machine, a series of rotatable bead forming rolls disposed in pairs, means for positioning between said pairs of rolls a plurality of rows of forms carrying articles to be treated, and means

for shifting the relative positions in said parts whereby said rolls simultaneously will form the beads on said articles.

9. In a bead forming machine, a series of rotatable bead forming rolls disposed in 70 pairs, means for positioning between said pairs of rolls a plurality of rows of forms carrying articles to be treated, and means for moving said forms longitudinally to cause said rolls to form the beads thereon. 75

10. In a bead forming machine, a series of horizontally disposed rotatable bead forming rolls arranged in pairs, a vertically movable table normally disposed to receive thereon in position between said rolls a plurality of rows of forms carrying the articles to be treated, and means for depressing said table and forms to cause said rolls to form the beads on said articles. 80

11. In a bead forming machine, a series 85 of horizontally disposed rotatable bead forming rolls disposed in pairs, a table disposed to receive thereon in position between said rolls a plurality of rows of forms carrying the articles to be treated, anti-friction means on said table for facilitating the automatic adjustment of said forms transversely of said table with respect to said bead forming rolls, and means for shifting the relative positions of said parts whereby 90 said rolls will form the beads on said table.

12. In a bead forming machine, a pair of horizontally disposed rotatable bead forming rolls, a vertically movable table normally disposed to receive thereon a form 100 carrying the article to be treated in position between said rolls, means for depressing said table and form to cause said rolls to form the bead on said article, and means for adjustably controlling the vertical movement of said table. 105

13. In a bead forming machine, a pair of horizontally disposed rotatable bead forming rolls, a vertically movable table normally disposed to receive thereon a form 110 carrying the article to be treated in position between said rolls, a lever for depressing said table and form to cause said rolls to form the bead on said article, and adjustable stops for limiting the movement 115 of said lever in either direction and correspondingly controlling the movement of said table and form.

14. In a bead forming machine, a pair of horizontally disposed rotatable bead forming rolls, a vertically movable table normally disposed to receive thereon a form carrying the article to be treated in position between said rolls, said table being spring-pressed upwardly, and means for depressing said table against the tension of said springs thereby causing said rolls to form the bead on the article to be treated. 120 125

15. In a bead forming machine, in combination with horizontally disposed rotat- 130

able bead forming rolls, a table disposed beneath said rolls, means for shifting said table vertically, and anti-friction means on said table adapted to receive a form carrying board and to facilitate the adjustment of the same laterally with respect to the bead forming rolls.

16. In a bead forming machine, in combination with horizontally disposed rotatable bead forming rolls, a table disposed beneath said rolls, means for shifting said table vertically, and elongated anti-friction rollers disposed transversely on said table and projecting forwardly thereof, said

15 rollers adapted to receive a form carrying

board as it is slid into position on said table and to facilitate its lateral adjustment thereon in respect to said bead forming rolls.

17. In a bead forming machine, a series of horizontally disposed rotatable bead forming rolls arranged in pairs, a table disposed beneath said rolls, means for shifting said table vertically, and side guides on said table comprising vertical plates of greater width than the thickness of said table at 20 their projecting portion but cut away flush with said table where connected thereto.

In testimony whereof I have hereunto affixed my signature.

THOMAS W. MILLER.
